UNITED STATES PATENT OFFICE

2,145,650

TUYÈRE

Gordon Fox, Chicago, Ill., assignor to Freyn Engineering Company, Chicago, Ill., a corporation of Maine

Application November 17, 1934, Serial No. 753,429
Renewed April 13, 1937

12 Claims. (Cl. 122—6.6)

The present invention relates to improvements in tuyères.

More particularly the present invention relates to tuyères such as are used in blast furnaces. Such tuyères are subjected to very high temperatures. It has been common to cool blast furnace tuyères by circulating water through an interior chamber of the tuyère. In order to perform efficient service the water should contact intimately with the metallic surface of the tuyère and should travel at high velocity. Water is an extremely poor conductor of heat and unless the circulation thereof is good, it is probable that steam is generated by the evaporation of a layer of water which lies immediately adjacent to the hot wall surface of the tuyère. This steam expands and thereby acquires a larger surface in contact with the cooling water. The heat of the steam is rather slowly absorbed by the water, causing the steam to be condensed and the temperature of the cooling water to be raised. In certain instances in prior practice the flow of water has not been effective in removing bubbles of steam from the wall surfaces, and such bubbles doubtless form a fairly efficient heat insulation between the inner wall surface of the tuyère and the water, thereby exaggerating the required temperature difference to give the required heat transfer.

An object of the present invention is to provide a water-cooled tuyère of simple construction in which the cooling water will be caused to pass at relatively high velocity in a relatively thin stream along the surfaces to be cooled.

A further object is to provide a tuyère of simple construction which will expose increased area of cooling surface to the cooling water of the tuyère, particularly in those portions of the tuyère exposed to the most heat.

Further objects will appear as the description proceeds.

Referring to the drawings—

Figure 1 is a view partly in section showing one embodiment of the present invention, the sectional part of Figure 1 being taken along the plane indicated by the arrows 1—1 of Figure 2;

Figure 2 is a transverse sectional view of the embodiment illustrated in Figure 1, Figure 2 being taken along the plane indicated by the arrows 2—2 of Figure 1;

Figure 3 is a sectional view taken along the plane indicated by the arrows 3—3 of Figure 1;

Figure 4 is a sectional view taken along the plane indicated by the arrows 4—4 of Figure 1;

Figure 5 is a view similar to Figure 1 but showing a modified construction; and

Figure 6 is a view similar to Figures 1 and 5 but showing a still further modification.

Referring first to the embodiment of the present invention illustrated in Figures 1 to 4, inclusive, said embodiment involves a two-part construction including the conical portion 10 and the back wall 11. According to the illustrated construction, the conical portion 10 and the back wall 11 are welded or otherwise united to form a rigid unitary construction. The conical portion 10 of the tuyère includes the outer wall 12 and the inner wall 13, which walls are disposed coaxially relative to each other. Said walls 12 and 13 are united at the forward end of the tuyère by the nose wall 14. The annular space defined by the outer wall 12, the inner wall 13, the nose wall 14 and the back wall 11 constitutes a space for cooling fluid. The present invention 20 contemplates a construction in which the cooling fluid is caused to enter from the rear end of the tuyère, circulating in a relatively thin stream along one of the conical walls of the tuyère and back along the other conical wall of the tuyère to 25 a discharge opening disposed a material distance from the inlet opening.

According to the structure shown in Figures 1 to 4, inclusive, cooling fluid is admitted through the inlet opening 15 in the back wall 11 of the 30 tuyère and is discharged through the outlet opening 16 in said back wall 11 spaced a material distance from the inlet opening 15. Communicating with the inlet opening 15 is the inlet pipe 17, which discharges into a region intermediate of 35 the length of the tuyère.

Disposed midway between the nose wall 14 and the back wall 11 is the partition wall 18, preferably disposed in substantially parallel relationship with the back wall 11. Said partition wall 40 18 is an annular member coaxially disposed with respect to the conical inner wall 13 and the conical outer wall 12. Said partition wall 18 may be held in place by means of the two struts 19—19, the positions of which are indicated in dotted 45 lines in Figure 3. Said partition wall 18 may also be supported by the inlet pipe 17. Said struts 19—19 and the inlet pipe 17 may be equi-spaced circumferentially with respect to the partition wall 18. As indicated in Figures 1 and 3, the inlet pipe 17 extends through the partition wall 18 and discharges into the space between said partition wall 18 and the nose wall 14.

The partition wall 18 has an internal diameter materially greater than the external diameter 55

of the adjacent portion of the conical nose wall 13. Supported by the partition wall 18 is the deflecting member, indicated as a whole by the numeral 20. Said deflecting member 20 in the embodiment of the invention illustrated in Figures 1 to 4, inclusive, may be described as mushroom-shaped, having the conical inner wall 21, the conical outer wall 22 and the connecting portion 23. As illustrated, the conical inner wall 21 of the deflecting member 20 is of greater length than the conical outer wall 22 thereof, for a purpose to be referred to presently. The inner wall 21 of the deflecting member 20 is secured to the inner periphery of the annular partition wall 18, leaving an annular channel 24 bounded by the outer periphery of the cone wall 13 and the inner periphery of the conical wall 21 of the deflecting member 20. The outer conical wall 22 of the deflecting member 20 is coaxial with but spaced from the outer cone wall 12. The connecting portion 23, which connects the conical walls 21 and 22 of the deflecting member 20, is spaced from the nose wall 14, whereby a tortuous passageway, which may be indicated in its entirety by the numeral 24, is provided between the rearmost edge of wall 22 and the partition wall 18, the outer cone wall 10 and the adjacent conical wall 22, the nose wall 14 and the adjacent connecting portion 23 and the inner cone wall 13 and the adjacent conical wall 21. Said conical walls 21 and 22 and the connecting portion 23 provide the annular channel 25. It is into this channel 25 that the inlet pipe 17 discharges.

As illustrated in Figures 1 and 2, the nose wall 14 of the tuyère has a plurality of radial barriers extending therefrom, which barriers are equi-spaced around the nose portion of the tuyère and are indicated by the numerals 26-26. Said barriers 26-26 provide between them radially disposed channels 27-27 for the flow of cooling medium. Said barriers 26-26 provide extended surfaces for heat transfer from the metal of the tuyère to the cooling medium in that region of the tuyère. The barriers 26-26 comprise corrugations or spaced projections extending inwardly from the nose wall 14. Said barriers, particularly the arcuate portions thereof disposed at the inner extremities of said barriers 26 adjacent to the walls 10 and 13, comprise corrugations extending from said walls 10 and 13 and merging with the corrugations extending from the nose wall 14.

The mode of operation of the invention illustrated in Figures 1 to 4 is substantially as follows: Water or other cooling medium enters the opening 15, flowing through the pipe 17 and discharging into the channel 25 of the deflecting member 20. Said water or other cooling medium divides, passing in two directions in the channel 25, proceeding to the channel 24 above referred to. Said water or other cooling medium is therefore caused to pass in a relatively thin stream along the outer cone wall 12 toward the nose wall 14. Upon reaching the region of the nose wall 14 the water or cooling medium passes through the radially disposed passageways 27-27, and, continuing along the passage 24, flows in a thin stream along the inner surface of the cone wall 13, discharging into the base portion 70 of the tuyère, that is, the region between the partition wall 18 and the back wall 11, whence said water or other cooling medium passes to the outlet opening 16. Because of the fact that the inlet opening 15 and the discharge opening 75 16 are located at spaced regions, the water in

passing through the tuyère will divide into two streams in flowing from the inlet opening to the discharge opening. It will be preferred to have the inlet opening 15 located substantially diametrically opposite to the discharge opening 16, 5 so that the water or other cooling medium will divide itself approximately equally in passing from the inlet to the outlet.

The above described embodiment of the present invention has certain advantages, as follows: It causes all of the water to flow along the outer cone wall 12 of the tuyère in the nose region thereof. It also causes all of the water to flow along the inner cone wall 13 in the nose region thereof. The water flows along these cone walls 15 in a relatively thin stream and at a velocity substantially higher than the velocity of flow in an ordinary tuyère. These walls are therefore much better cooled than in an ordinary tuyère. In the nose region of the tuyère the water is caused to 20 flow in restricted channels and hence will flow at fairly high velocity. The water contacts with the radial barriers in the nose portion of the tuyère, flowing along the surfaces thereof with a scouring action, so that if bubbles of steam 25 should tend to form at the nose portion of the tuyère, said bubbles will be scoured off efficiently. If preferred the direction of flow between the ports 15 and 16 may, of course, be reversed.

A somewhat similar construction is illustrated 30 in Figure 5. In the embodiment illustrated in Figure 5 an annular deflecting member 28 is provided, which, for cheapness of construction, may be hollow. This deflecting member 28 is coaxially disposed with respect to the outer cone wall 35 12 and the inner cone wall 13 and is carried by the back wall 11. Said deflecting member is spaced from the outer cone wall 12, the nose wall 14 and the inner cone wall 13. Said back wall 11 is provided with the inlet opening 15 and the outlet 40 opening 16, which openings are preferably disposed on a diameter of the back wall 11.

In the construction illustrated in Figure 5 the water entering through the inlet 15 divides, flowing along the outer cone wall 11 through the 45 channels provided by the radial barriers 26-26 and back along the inner cone wall 13, discharging through the outlet 16. It will be understood, of course, that if preferred the flow of water may be reversed. The water flows along the walls of 50 the tuyère in a thin stream at relatively high velocity, at the same time flowing circumferentially half way around the tuyère.

The construction illustrated in Figure 6 embodies features of construction of the two embodiments above described. According to the construction illustrated in Figure 6, the annular partition wall 29 is provided, which, similar to the construction illustrated in Figure 1, may be supported by the inlet pipe 17 and a pair of struts 55 60 similar to the struts 19-19 shown in Figure 3. Secured to the partition wall 29 is the deflecting member 30 disposed coaxially with the outer cone wall 12 and the inner cone wall 13 but spaced from said cone walls.

In the operation of the construction shown in Figure 6, cooling water through the inlet pipe 17 is directed first to the nose portion of the tuyère, that is, the space between the partition wall 29 and the nose wall 14, flowing first past 70 one of the cone walls and back past the other of the cone walls, efficiently cooling the nose portion of the tuyère, where cooling is most needed. As in the other two embodiments above described, the water, while passing longitudinally 75

with respect to the cone walls 12 and 13, also divides circumferentially.

All of the illustrated embodiments of the present invention have the advantage of causing the cooling medium to flow in a relatively thin stream along the inner and outer cone walls. The efficient cooling effect of this flow of water is supplemented by the extended contact between the cooling water and the barriers 26-26 in the nose portion of the tuyère, which minimizes the formation of steam bubbles in those portions of the tuyère where heat units are likely to accumulate.

Though certain preferred embodiments of the present invention have been described in detail, many modifications will occur to those skilled in the art. It is intended to cover all such modifications that fall within the scope of the appended claims.

What is claimed is:

1. In a tuyère, in combination, an inner cone wall, an outer cone wall, a back wall and a nose wall providing an annular cooling jacket, said back wall being provided with an inlet and an outlet for cooling medium, said nose wall on the inside surface thereof being provided with a series of barriers providing therebetween parallel passageways between said cone walls, and means within said jacket for directing cooling medium radially of said jacket in parallel through said parallel passageways.

2. In a tuyère, in combination, an inner cone wall, an outer cone wall, a back wall and a nose wall providing an annular cooling jacket, said back wall being provided with an inlet and an outlet for cooling medium, and an annular deflecting member within said jacket for directing cooling medium from said inlet first along one of said cone walls longitudinally of said tuyère and back along the other of said cone walls longitudinally of said tuyère, said nose wall on the inside surface thereof being provided with a series of barriers providing therebetween parallel passageways between said cone walls, said annular deflecting member being disposed in position to direct said cooling medium in parallel through said parallel passageways.

3. In a tuyère, in combination, inner and outer cone walls, a back wall and a nose wall forming an annular cooling jacket, said back wall being provided with a water inlet and a water outlet, an annular deflecting member disposed within said jacket, said deflecting member being spaced from said cone walls and said nose wall, said inlet and said outlet having communication with the annular spaces on the inside and outside of said annular deflecting member, said nose wall on the inside surface thereof being provided with a series of barriers providing therebetween parallel passageways between said cone walls, said annular deflecting member being disposed in position to direct said cooling medium in parallel through said parallel passageways.

4. In a tuyère, in combination, inner and outer cone walls, a back wall and a nose wall providing a cooling jacket transversely with respect to the axis of said tuyère, an annular partition wall mounted in said jacket, an annular deflecting member carried by said annular partition wall, a pair of spaced ports in said back wall, and means providing communication between one of said ports and the annular space on one side of said deflecting member, the other of said ports having communication with the other side of said deflecting member, said nose wall on the inside

surface thereof being provided with a series of barriers providing therebetween parallel passageways between said cone walls, said annular deflecting member being disposed in position to direct said cooling medium in parallel through said parallel passageways.

5. In a tuyère, in combination, inner and outer cone walls, a back wall and a nose wall providing an annular cooling chamber, an annular partition wall within said chamber, an annular deflecting member carried by said annular partition wall in the nose portion of said tuyère, said annular deflecting member comprising a folded-over member having an annular space between the folds thereof, said back wall having a pair of ports, one of which has communication with the annular space between the folds of said deflecting member, said annular space between said folds having communication with the other of said ports.

6. In a tuyère, in combination, inner and outer cone walls, a back wall and a nose wall providing an annular cooling chamber, an annular partition wall within said chamber, an annular deflecting member carried by said annular partition wall in the nose portion of said tuyère, said annular deflecting member comprising a folded-over member having an annular space between the folds thereof, said back wall having a pair of ports, one of which has communication with the annular space between the folds of said deflecting member, said annular space between said folds having communication with the other of said ports, said ports being diametrically opposed relative to one another.

7. In a tuyère, in combination, inner and outer cone walls, a back wall and a nose wall providing an annular cooling chamber, an annular partition wall within said chamber, an annular deflecting member carried by said annular partition wall in the nose portion of said tuyère, said annular deflecting member comprising a folded-over member having an annular space between the folds thereof, said back wall having a pair of ports, one of which has communication with the annular space between the folds of said deflecting member, said annular space between said folds having communication with the other of said ports, said nose wall on the inside surface thereof being provided with a series of barriers providing therebetween passageways between said cone walls.

8. In a tuyère, in combination, inner and outer cone walls, a back wall and a nose wall providing an annular cooling chamber, an annular partition wall within said chamber, an annular deflecting member carried by said annular partition wall in the nose portion of said tuyère, said annular deflecting member comprising a folded-over member having an annular space between the folds thereof, said back wall having a pair of ports, one of which has communication with the annular space between the folds of said deflecting member, said annular space between said folds having communication with the other of said ports, said ports being diametrically opposed relative to one another, said nose wall on the inside surface thereof being provided with a series of barriers providing therebetween passageways between said cone walls.

9. In a tuyère, in combination, inner and outer cone walls, a back wall and a nose wall providing a cooling chamber, an annular partition wall in said chamber midway of the length thereof, an annular deflecting member carried by said an-

nular partition wall, said deflecting member being U-shaped in cross-section whereby to provide an annular space intermediate of the legs of such U-shaped conformation, one of said legs providing a passageway between said annular partition wall and one of said cone walls, a pair of ports in said back wall, and means providing communication from one of said ports through said annular partition wall to the annular space between the legs of said deflecting means, the annular spaces on the two sides of said deflecting means having communication with each other and with said other port.

10. In a tuyère, in combination, inner and outer cone walls, a back wall and a nose wall providing a cooling chamber, an annular partition wall in said chamber midway of the length thereof, an annular deflecting member carried by said annular partition wall, said deflecting member being U-shaped in cross-section whereby to provide an annular space intermediate of the legs of such U-shaped conformation, one of said legs providing a passageway between said annular partition wall and one of said cone walls, a pair of ports in said back wall, and means providing communication from one of said ports through said annular partition wall to the annular space between the legs of said deflecting means, the annular spaces on the two sides of said deflecting means having communication with each other and with said other port, said ports being diametrically opposite to each other.

11. In a tuyère, in combination, inner and outer cone walls, a back wall and a nose wall providing a cooling chamber, an annular partition wall in said chamber midway of the length thereof, an annular deflecting member carried by said annular partition wall, said deflecting member being

U-shaped in cross-section whereby to provide an annular space intermediate of the legs of such U-shaped conformation, one of said legs providing a passageway between said annular partition wall and one of said cone walls, a pair of ports in said back wall, and means providing communication from one of said ports through said annular partition wall to the annular space between the legs of said deflecting means, the annular spaces on the two sides of said deflecting means having communication with each other and with said other port, said nose wall on the inside surface thereof being provided with a series of barriers providing therebetween passageways between said cone walls.

12. In a tuyère, in combination, inner and outer cone walls, a back wall and a nose wall providing a cooling chamber, an annular partition wall in said chamber midway of the length thereof, an annular deflecting member carried by said annular partition wall, said deflecting member being U-shaped in cross-section whereby to provide an annular space intermediate of the legs of such U-shaped conformation, one of said legs providing a passageway between said annular partition wall and one of said cone walls, a pair of ports in said back wall, and means providing communication from one of said ports through said annular partition wall to the annular space between the legs of said deflecting means, the annular spaces on the two sides of said deflecting means having communication with each other and with said other port, said ports being diametrically opposite to each other, said nose wall on the inside surface thereof being provided with a series of barriers providing therebetween passageways between said cone walls.

GORDON FOX.
